VIBRATORY DEVICE FOR CONTROLLING
DISCHARGE FROM A HOPPER CONTAIN-
ING A POWDERED OR A SMALL-SIZE
GRANULAR HOMOGENEOUS SUBSTANCE

Gérard Bardet, Paris, France

Application April 15, 1948, Serial No. 21,278
In France October 20, 1947

8. Claims. (Cl. 222—197)

1

This invention is concerned with a device designed to control the discharge of a hopper containing a powdered or a small-size granular homogeneous substance such as flour, granulated sugar, rice, coffee and the like, with the aid of which device the outflow of the substance concerned can be adjusted or stopped altogether.

The device is composed primarily of a movable element provided at the outlet of the hopper and consisting of at least two parallel plane and horizontal plates which are equal in width, arranged at equal distances from one another, and interconnected by vertical side plates. The distance between the plates is dependent on the character of the substance present in the hopper. The ends of said plates next to the hopper are offset with respect to one another in staircase-like fashion.

When a steady outflow of the substance is to be obtained the movable element according to the invention is reciprocated rapidly, the amplitude and frequency of such a reciprocatory motion being constant and dependent on the character of the substance; the direction of the movement is slightly at an angle to the planes of the plates. The upper plate of the movable element is reciprocated with a slight clearance below the lower edge of the hopper wall which faces said movable element while the lower plate is reciprocated with a slight clearance below the lower edge of the opposite wall. The said vertical side-plates slide outside the hopper outlet side-walls, with such a clearance that any friction therebetween is so prevented. Moreover, the said hopper outlet side-walls are notched in such a way that a sufficient clearance is provided between the same and the end of the movable plates, so as to prevent any impact of said plates against said side-walls.

Each time the set of plates dips in the hopper, slices of the substance are cut or separated between the successive plates, and said slices crumble and lay in a broken up and powdered state on the plate on which they rest. At each following half-period of the reciprocating movement, that is when the set of plates moves in the direction opposite to the hopper, the particles of the substance composing the cut and crumbled slice commence being swept along towards the outside of the hopper, owing to the effect of the said reciprocating movement, according to the known principle of the shaking chutes.

Effectively, it is known that when an approximately horizontal plate is actuated with a rapid

2

reciprocating rectilinear movement of translation according to a direction at a small angle with the plane of said plate, the solid particles then on the plate move on the surface of same in a direction which is the projection on said plate of the upward motion part of said reciprocating rectilinear movement of the plate.

The discharge of substance will cease as soon as the reciprocatory motion of the plate system is stopped, due to the baffle effect of the same and to the friction of the substance on the plates. Of course, a still quicker cut-off can be obtained by providing the plates with a knurled, ridged, honeycombed or like friction-increasing surface.

The distance between any two adjacent plates depends on the character of the substance dealt with. For the discharge of a given substance, said distance should be sufficiently large to allow the substance to flow between each pair of plates as the movable element is reciprocated in the manner explained. Said distance should be moreover sufficiently small, so that the layer of the substance on every plate of the element should be thin enough to cause the fall of the substance from the rear end of the plates to be stopped as soon as the element is pulled up.

The amplitude, frequency and direction of the reciprocatory movement should be such that the substance is suitably cut through and carried away.

The invention is also concerned with various applications of the device considered.

Further features of the invention will be pointed out in the following description in which reference is had to the appended drawing in which:

Figures 1a, 1b and 1c are longitudinal sections of a device according to the invention at different stages of its operation.

Figure 2 is a front view of the device according to Figs. 1a, 1b and 1c.

Figure 3 is a longitudinal section of a modification.

Figures 4a, 4b and 4c are longitudinal sections of a further modification at different stages of its operation.

Figures 5 and 6 are respectively elevational and top views of the device provided with its reciprocating mechanism.

Referring now to the embodiment shown in Figs. 1a, 1b and 1c, 1 designates the discharge end of a hopper which contains a powdered or a small-size granular substance. 3, 4, 5, 6, 7, 8 denote the plates providing the movable element. These plates have all the same width, as may be seen in Fig. 2. They are parallel to each

other, and the distance between any two consecutive plates is the same. They are approximately horizontal; they are held firm with each other by two vertical side plates 9, 10. As represented in Figs. 1a, 1b, 1c, the ends of the plates which are engaged into the outlet of the hopper, are arranged with respect to one another in stepwise disposition. Through any reciprocating device, immaterial with regard to the invention, the set of plates can be endowed with a reciprocating movement towards and from the outlet of the hopper. This reciprocating movement is effected along a direction F meeting said parallel plates at a small angle α , in the range of about 5° to 10°. The location of this angle α must be as represented in Figs. 1a, 1b, 1c, 3, 4a, 4b, 4c, that is such that during the half-period of the reciprocating movement directed towards the hopper outlet, the movable element is moved slightly downwards and during the half period directed from the hopper outlet, the movable element is moved slightly upwards. Consequently, the plates are dipped into the substance present in the outlet of the hopper according to a slightly downward direction and removed from the outlet of the hopper according to a slightly upward direction.

In Fig. 1a, the movable element is shown in the extreme position remote from the hopper, before the beginning of the reciprocating movement. In Fig. 1b, it is shown at the end of the first half-period of the reciprocating movement, that is at the end of the first dipping movement into the substance; this first movement is carried out according to a slightly downward direction parallel to the arrow F.

At the end of this half-period, slices of the substance are cut between the successive plates. Said slices crumble at the beginning of the following half-period.

In Fig. 1c, the movable element is shown at the end of the second half-period, that is at the end of the upward half-period of the reciprocating movement. At this moment, the slices of the powdered substance that have been scooped between the successive plates 3 and 4, 4 and 5 . . . , 7 and 8, lie crumbled on the plates and they have begun to be swept away on the plates from the slicing edge thereof, that is towards the left on Fig. 1c. During this half-period, the substance in the hopper has settled onto the plates 4, 5, 6, 7 and 8 ready for a new scooping when the movable element is dipped anew in the hopper, that is at the following half-period of the reciprocating movement. New slices will then be cut, will then crumble on the plates and will move away from the slicing edges, while the particles of the previously cut off slices move a little further towards this same direction. It will be the same at each of the following periods, and the material will be progressively jogged along on the surface of each of the plates 4 to 8.

The frequency of the reciprocating movement, for a flow of powdered sugar, may be comprised between 10 and 100 cycles per second; the frequency, as the amplitude of the movement, is likely to vary within large limits dependent on the nature of the broken up substance contained in the hopper.

Fig. 3 in which the numerals have the same 70 significance as in the preceding figures, represents a modification in which all the plates except the one located lowermost are formed at their hopper-engaging end with a ridge or the like as indicated at 3', 4', 5', 6', 7'; the purpose of the 75

said ridges is to prevent the material discharged from being compressed between any pair of successive plates and thus to facilitate the progression of said material since the thickness of the slice of material chopped away is less than the distance from one plate to the next one. In addition, the provision of such ridges will obviate the detrimental consequences of any difference in height along the channels formed by the plates.

10 A further modification is illustrated in Figs. 4a, 4b, 4c in which the plate ends next to the hopper are sloping downwards while the plates are generally horizontal; in said figures 13, 14, 15, 16 designate the plates proper and 13', 14', 15', 16', their respective sloping ends. Preferably, the bend in each plate is formed plumb below the edge of the next higher plate. Preferably also, the direction F' of the reciprocatory motion of the plate set is parallel with the ends 13', 14', 15', 16' of the plates.

15 As shown in Fig. 4a the movable element consists of a set of four plates 13, 14, 15, 16 and occupies its starting position. As shown in Fig. 4b the said element is at the end of its stroke towards the hopper and all the plates except the one 16 located lowermost have chopped practically equal slices of the material. Each slice rests on the plate next below.

20 As shown in Fig. 4c the plates are again in their starting position ready for a new chopping process while the material already present in the various channels is carried away in the manner explained hereinbefore.

25 The advantage with such an arrangement is that the material cannot be wedged between the plates (see Fig. 4) since a layer of material is scooped away the thickness of which is less than the height between any two successive plates in their horizontal portions. Moreover, owing to the absence of any ridge and to the fact that the plate ends dip into the material in directions parallel with their own slopes, any ramming of the material is thus prevented.

30 An embodiment of a movable element provided with conventional reciprocating means as mentioned hereinabove has been represented by mere way of exemplification in Figs. 5 and 6. These reciprocating means are known per se. They consist of an electromagnet 20, of which the movable armature 21 is connected with the movable element 22 by means of a fork 23. A flat spring 24 connects this reciprocable fork to a fixed frame 25. A flexible strip 26 supports the front part of the fork 23.

35 The line according to which the armature 21 is reciprocated is at a slight angle α with the plates of the movable unit 22, in the way as indicated at Fig. 5.

40 The device according to the invention lends itself to various applications, for instance in weighing and bagging apparatus in the operation of which the material is jogged along to a point above and poured into a receptacle operatively connected with a scale-beam. As soon as the desired weight is reached the scale brings the device to rest, whereby the flow of material is stopped.

45 What I claim is:

1. In a device for dispensing comminuted material, a downwardly opening discharge spout having a longer rear wall, shorter front wall and connecting side walls, a movable element for controlling the discharge of material from said spout, comprising a plurality of spaced, superposed par-

allel plates disposed approximately horizontally at the lower end of said spout and side walls connecting the plates, said plates being arranged in staircase-like fashion with the rear edges of a plate stepped forwardly from the rear edge of the plate below it, the rear edge portion of the lowermost plate extending rearwardly beyond the rear wall of said spout so as to close said spout when said element is stationary and the rear edge of the uppermost plate extending under the front wall of the spout and into said spout but terminating short of the rear wall thereof, and means for vibrating said movable element with a rapid reciprocating movement in a direction forwardly-and-upwardly and rearwardly-and-downwardly relative to said plates to cause the material to be sliced off and to flow forwardly on said plates and be discharged from the forward edges thereof.

2. In a device for dispensing comminuted material, a downwardly opening discharge spout having a rear wall, a front wall having a lower edge higher than the lower edge of said rear wall, and connecting side wall portions, a movable element controlling the discharge of material from said spout, comprising a plurality of spaced superposed parallel plates disposed approximately horizontally at the lower end of said spout and side walls connecting the plates, the lowermost plate extending rearwardly beyond the rear wall of said spout so as to close said spout when said element is stationary and the rear edges of superposed plates being stepped successively forwardly in staircase-like manner so that, proceeding upwardly from the lowermost plate, successive plates extend step-by-step lesser distances into said spout, and means for vibrating said movable element to produce flow of said material along said plates in a direction toward the front edges of said plates.

3. In a device for dispensing comminuted material, a downwardly opening discharge spout having a bottom edge that is lower at the rear than at the front, a movable element normally closing the lower end of said spout and comprising a plurality of spaced superposed parallel plates disposed approximately horizontally and side walls connecting said plates, the lowermost plate extending rearwardly under the rear bottom edge of the spout, the uppermost plate extending under the front bottom edge of the spout and intervening plates extending progressively greater distances into said spout so that the rear edges of said plates are stepped downwardly and rearwardly in staircase-like manner, and means for vibrating said element with a forward and rearward motion to cause the rear edges of said plates, other than the lowermost plate, to successively bite into comminuted material in said spout and to produce flow of said material along the plates in a forward direction.

4. In a device for dispensing comminuted material, a downwardly opening discharge spout having a bottom edge that is lower at the rear than at the front, a movable element normally closing the lower end of said spout and comprising a plurality of spaced superposed parallel plates disposed approximately horizontally and side walls connecting said plates, each of said plates other than a bottom plate having a rear edge portion in the lower part of the spout, the distance said plates extend into the spout progressively increasing, proceeding from the top plate, and the bottom plate extending rearward-

ly under the rear bottom edge of the spout, and means for vibrating said movable element with a forward and rearward movement to produce flow of said material along the plates in a forward direction.

5. In a device for dispensing comminuted material, a downwardly opening discharge spout having a bottom edge that is lower at the rear than at the front, a movable element normally closing the lower end of said spout and comprising a plurality of spaced superposed parallel plates disposed approximately horizontally and side walls connecting said plates, the lowermost plate extending rearwardly under the rear bottom edge of said spout and the rear edges of superposed plates being stepped successively forwardly in staircase-like manner so that, proceeding upwardly from the lowermost plate, successive plates extend progressively lesser distances into said spout, and the rear edge portions of said plates other than the lowermost plate having downwardly extending portions, and means for vibrating said movable element with a forward and rearward movement to produce flow of said material along the plates in a forward direction.

6. In a device for dispensing comminuted material, a downwardly opening discharge spout having a bottom edge that is lower at the rear than at the front, a movable element normally closing the lower end of said spout and comprising a plurality of spaced superposed parallel plates disposed approximately horizontally and side walls connecting said plates, the lowermost plate extending rearwardly under the rear bottom edge of said spout and the rear edges of superposed plates being stepped successively forwardly in staircase-like manner so that, proceeding upwardly from the lowermost plate, successive plates extend progressively lesser distances into said spout, said plates other than the lowermost plate having downwardly projecting ribs adjacent their rear edges, and means for vibrating said movable element with a forward and rearward movement to produce flow of said material between the plates in a forward direction.

7. In a device for dispensing comminuted material, a downwardly opening discharge spout having a bottom edge that is lower at the rear than at the front, a movable element normally closing the lower end of said spout and comprising a plurality of spaced superposed parallel plates disposed approximately horizontally and side walls connecting said plates, the lowermost plate extending rearwardly under the rear bottom edge of said spout and the rear edges of superposed plates being stepped successively forwardly in staircase-like manner so that, proceeding upwardly from the lowermost plate, successive plates extend progressively lesser distances into said spout, said plates having rear edge portions that slope rearwardly and downwardly relative to the plane of the main portions of the plates, and means for vibrating said movable element with a forward and rearward movement to produce flow of said material between the plates in a forward direction.

8. In a device for dispensing comminuted material, a downwardly opening discharge spout having a bottom edge that is lower at the rear than at the front, a movable element normally closing the lower end of said spout and comprising a plurality of spaced superposed parallel plates disposed approximately horizontally and

side walls connecting said plates, the lowermost plate extending rearwardly under the rear bottom edge of said spout and the rear edges of superposed plates being stepped successively forwardly in staircase-like manner so that, proceeding upwardly from the lowermost plate, successive plates extend progressively lesser distances into said spout, said plates having rear edge portions that slope rearwardly and downwardly relative to the plane of the main portions of the plate, the juncture of said sloping portion with the main horizontal portion of each plate being approximately directly below the rear edge of the next higher plate, and means for vibrating said movable element with a forward and rearward movement to produce flow of said material between the plates in a forward direction.
